UNITED STATES PATENT OFFICE.

EDWARD L. KELLAN, OF CHICAGO, ILLINOIS.

FLUSH-VALVE.

1,385,456.

Specification of Letters Patent. Patented July 26, 1921.

Application filed May 15, 1916. Serial No. 97,522.

To all whom it may concern:

Be it known that I, EDWARD L. KELLAN, a citizen of the United States, and a resident of Chicago, in the county of Cook and State of Illinois, have invented certain new and useful Improvements in Flush-Valves; and I do hereby declare that the following is a full, clear, and exact description thereof, reference being had to the accompanying drawings, and to the characters of reference marked thereon, which form a part of this specification.

This invention relates to improvements in flush valve devices for supplying a desired volume of liquid through a desired interval of time from a source of liquid supply under pressure to a place or places of use for the liquid.

The present invention relates to that type of valve device commonly known as semi-automatic wherein the valve is opened for the flow of liquid therethrough through the instrumentality of a manually operable device, the valve being subsequently closed by reason of the differential pressures from the source of supply acting on the valve parts.

The invention consists in the arrangement and combination of the elements shown in the drawings and described in the specification and is pointed out in the appended claims.

In said drawings:

Figure 1 is a vertical axial section of a valve embodying my invention.

35 Figs. 2 and 3 are transverse sections on the lines 2-2 and 3-3 respectively of Fig. 1.

As shown in the drawings, 10 designates the valve casing which is provided at one end with an inlet branch 11 and at its side with an outlet branch 12. To the inlet branch, and as herein shown as made a part separate from and threaded to the casing is a tubular adapter element 11' which is 45 shown as having a reduced interiorly threaded end to receive a pipe adapted for connection to a source of the flushing fluid. The said casing 10 is extended upwardly to constitute a timing cylinder 14, the purpose of 50 which will be hereinafter described, and said timing cylinder is closed at its upper end by a cap 15 between which and the end of the cylinder is interposed a yielding packing 16. Contained within the enlarged 55 lower screw threaded end 17 of the casing is a perforated diaphragm 18 which is confined

between a downwardly facing annular shoulder 19 and the upper end of the screw threaded inlet extension 11', packing washers 20, 20, being interposed between the 60 coacting clamping parts to provide liquid proof joints. The lower side of said diaphragm 18 is constructed to form the body seat 21 of the valve. Formed also on the lower side of the diaphragm is an annular, 65 downwardly extending flange or lip 22 that constitutes a guide for the main valve 23, said diaphragm being readily removed for the purpose of regrinding or replacement when the extension 11', or alternately the 70 flushing fluid supply pipe is detached, it being exposed at and freely accessible from the end of the casing. Said valve engages the seat 21 to control the flow of flushing fluid through the device, and is guided in movement in said flange 22. Said valve is carried by the lower end of a hollow stem 25 which latter terminates at its upper end in a motor piston 26 provided with an upwardly direct annular flange 27 which reciprocates 75 within the cylinder. The seating face of the main valve is preferably formed on a yielding washer 28 that is held in place between a flanged portion 29 of the hollow valve stem and a disk member 30 which constitutes 80 the principal body of the valve; said disk member 30 being provided with a downwardly extending flange 31 which is internally screw threaded to engage external 85 screw threads on the lower end of the hollow valve stem. Said hollow valve stem is provided with a series of guide wings 32 which engage with a guiding fit the opening 90 in the diaphragm 18. The disk member 30 of the valve is provided with an upstanding marginal lip 34 which loosely fits within the flange or lip 22 of the diaphragm 18, the purpose of which is to cut off the full 95 flushing flow of the liquid and to thereafter permit a restricted after-fill flow, also 100 to prevent foreign matter from lodging on the seat.

On the lower end of the hollow stem is formed a seat that is engaged by a relief valve 35 which is carried by the lower end 105 of a stem comprising a lower enlarged portion 36 and an upper portion 37. Said lower portion of the stem is preferably fluted or winged and has guiding engagement with the bore of the hollow stem 25 so as to thereby 110 permit liquid to pass upwardly through the hollow valve stem and above the piston

or plunger 27 when the relief valve is open. The upper portion 37 of the stem, which may consist of a short rod, extends through a stuffing box 38 in the lower wall 39 of the cylinder 14 and terminates at its upper end in a head 40. Said stuffing box extends through the plunger 27 and into the hollow main valve stem, so as to thereby enable the casing to be materially shortened. 41 designates a restoring spring for the relief valve which is located within the cylinder 14. It surrounds the stem 37 and is interposed between the head 40 and the follower member 42 of the stuffing box. The arrangement is such that the said spring is under compression when the relief valve is closed so that the yieldable packing of the stuffing box 38 is maintained under compression.

Located within the cylinder 14 is a piston 45 comprising upper and lower disk-like members and a cup leather 46 clamped between the same. Said disk members are screw threaded to an extension fitting 48 which is in turn screw threaded to the lower end of a hollow operating stem 49 that extends upwardly from the piston and outwardly through a suitable stuffing box 50 carried by the closing cap 15 of the cylinder 14. As herein shown said stem embraces an extension member 51 which is screw threaded to the upper end of the main portion of the stem and extends into and guidingly engages a neck 52 which is formed integral with and extends upwardly from the external member 53 of the stuffing box 50. The operating stem is provided with a removable hand piece 54 shown as screw threaded thereto. The compressible member of the stuffing box 50 is maintained under compression by a spring 55 interposed between the follower member of the stuffing box and an internal shoulder between the exterior member of said stuffing box and the neck 52.

The said cylinder 14 is adapted to be filled 45 with a body of substantially non-compressible liquid of a character other than that of the flushing liquid, such as a relatively heavy oil, to constitute in connection with the piston 45 a timing device to control the closing movement of the relief valve 35; a by-pass being provided to permit the passage of the liquid from the upper to the lower sides of the piston as it is reciprocated in the cylinder. As herein shown the liquid may be by-passed from the lower to the upper side of the piston around the cup leather packing of the piston when the piston is depressed to open the relief valve 35. Said packing, however, prevents by-passing 50 of the liquid around the piston in the upward movement thereof and in order to permit by-passing of the liquid from the upper to the lower side of the piston when the piston rises a by-pass is provided which comprises an axial passage 56 within the termi-

nal fitting 48 that opens below the piston and a radial passage 57 which communicates with the axial passage and opens above the piston. The said by-pass thus formed is adapted to be controlled by a regulating valve 58 formed on the lower screw threaded end of a rod 59 that extends through the hollow piston operating stem and is screw threaded at its lower end to engage internal screw threads of the axial passage 56. 75 Said rod is slotted at its upper end to receive a screw driver or like implement, when the hand piece 54 is removed, whereby the by-pass may be more or less opened to permit a faster or slower closing movement 80 of the relief valve 35, as desired.

In order to prevent the entrance of particles carried in suspension by the liquid into the timing piston by-pass during the upward movement of the piston, such as 85 would tend to clog the by-pass, I have provided a screen 60 of the form shown in Figs. 1 and 2 which surrounds the terminal fitting 48 and is held in place by a clamping member 61 which is screw threaded to the 90 operating stem 49 near its lower end and bears at its lower annular edge against the margin of the screen and fits within an up-standing lip 62 of the upper piston disk member, as shown in Fig. 1. The said 95 clamping member 61 is provided with one or more openings 63 through which liquid may flow.

In the use of the device it will be understood that the branch 11 is connected 100 through the extension 11' to a source of flushing liquid supply under pressure and that the branch 12 is connected with the space which is to receive supplies of liquid intermittently passed through the valve device. When it is desired to operate the flush valve pressure is applied to the hand piece 54 of the operating stem. Such pressure depresses the piston 45 and therethrough acts upon the relief valve stem to open the latter 110 valve. As soon as the relief valve is opened liquid passes through the hollow main valve stem to the upper side of the motor piston and overbalances the inlet pressure on the main valve to open the main valve to the required extent to permit a flushing flow of liquid therethrough. The opening movement of the main valve continues until the lip or flange 27 of the piston or plunger 26 is depressed below the upper side of the outlet 12, whereupon water escapes from the upper side of the piston through said outlet, thereby reducing the pressure tending to open the valve. When the valve is thus fully opened and manual pressure is released from the relief valve operating stem 49, the spring 41 acts in conjunction with the inlet pressure to close the main and relief valves; the liquid above the piston or plunger 26 escaping between the same and 130

the cylinder wall as said piston rises in the casing. The time required to close said main valve is governed by the regulation of the by-pass in the piston 45. If the by-pass 5 be checked down to permit the liquid to pass slowly therethrough the duration of the closing period of the main valve will be longer than if the by-pass valve be adjusted to permit the liquid to flow more freely 10 through said by-pass.

It will be observed that the relief valve which controls the opening movement of the main valve is operated directly by pressure on the operating stem of the piston 45, said 15 parts being arranged axially in line with each other so that the valve is operated with a minimum expenditure of manual power. It will be furthermore observed that while the valve stem is thus in a position to be 20 acted upon by the piston, said parts are separately made. This arrangement is advantageous inasmuch as it simplifies the manufacture of the valve and reduces its cost. It is also advantageous in that the piston 25 ton may be removed from the timing cylinder without disturbing the main or relief valve, and therefore without the necessity of shutting off the water or other liquid, when such removal of the piston is desired 30 to repair the packing thereof or to clear the by-pass in case of an obstruction or to replenish the liquid of the timing cylinder. The construction shown and described also enables the main and relief valves to be removed 35 without disturbing the timing piston when such removal is desired for the purpose of repairing or replacing said parts, it only being necessary to remove the branch 11, whereupon, by holding the relief valve 40 stem from rotation, said valve and the main valve, as well as the diaphragm 18, may be removed downwardly through the open lower end of the casing.

In practice I prefer to provide a shoulder 45 on the relief valve stem which is adapted to engage, when the stem is depressed, an opposing shoulder 66 within the hollow main valve stem, the parts being so proportioned that said shoulders are 50 brought into contact when the relief valve stem is depressed sufficiently to open the latter valve the required distance, so as to positively open the main valve by manual power in the event that the movable parts 55 should accidentally stick.

It will be understood that the structural details of the flush valve described may be

varied from those shown and herein described within the spirit and scope of the claims hereto appended and that the invention is not limited to such details except as to claims wherein the same are specifically set forth, and as imposed by the prior art. 60

I claim as my invention:—

1. A flush valve of that kind which is controlled by differential pressures acting on the operative parts thereof from a source of liquid supply under pressure, comprising a casing provided with an inlet and with an outlet, a main valve between them, a relief valve controlling the main valve, a liquid controlled, regulable timing element in alinement with said relief valve for opening the relief valve and for timing the closing movement of the valve device, said timing element being separate from and removable independently of the relief valve and associated parts, means coöperating with the relief valve for holding it and its associated parts closed and intact when the timing element is removed, and means constructed to permit removal of the main valve without disturbing said timing element. 75

2. A flush valve of that kind which is controlled by differential pressures acting on the operative parts thereof from a source of liquid supply under pressure, comprising a casing provided with an inlet and with an outlet, a main valve between them, a relief valve controlling the main valve, a liquid controlled, regulable timing element in alinement with said relief valve for opening the relief valve and for timing the closing movement of the valve device, said timing element being separate from and removable independently of the relief valve and associated parts, and means coöperating with the relief valve for holding it and its associated parts closed and intact when the timing element is removed, said casing being provided at its inlet, which is at the end of the casing, with a seat member which is exposed at said end for ready removal when a flush liquid conduit threaded to 90 said casing is removed. 95

In testimony that I claim the foregoing as my invention I affix my signature in the presence of two witnesses, this 6th day of January A. D. 1916.

EDWARD L. KELLAN.
